UNITED STATES PATENT OFFICE.

ERNST F. W. ALEXANDERSON, OF SCHENECTADY, NEW YORK, ASSIGNOR
TO GENERAL ELECTRIC COMPANY, A CORPORATION OF NEW YORK.

ALTERNATING-CURRENT MOTOR.

No. 841,610.

Specification of Letters Patent.

Patented Jan. 15, 1907.

Application filed November 9, 1905. Serial No. 286,510.

To all whom it may concern:

Be it known that I, ERNST F. W. ALEXANDERSON, a subject of the King of Sweden, residing at Schenectady, county of Schenectady, State of New York, have invented certain new and useful Improvements in Alternating-Current Motors, of which the following is a specification.

My invention relates to alternating-current motors of the induction type; and one of its objects is to provide a novel arrangement of and method of control for such motors whereby a plurality of speeds may be obtained bearing any desired ratio to each other without the use of a special winding and with a smaller number of terminal connections than has been possible heretofore.

My invention in certain of its aspects is particularly applicable to motors adapted for operation on three-phase current; but in other of its aspects it is not limited to a motor of any particular number of phases nor even necessarily to a motor designed for operation at a plurality of speeds.

25 Certain special connections are now well known in the art by means of which a three-phase induction-motor may be caused to operate at a plurality of different speeds bearing a certain ratio to each other without employing a special type of winding. Such, for instance, is the connection shown in Patent No. 725,415, Dahlander and Lindstrom, which shows a simple connection of means by which two speeds of a ratio of two to one 30 may be obtained. When certain other speed ratios are required, however, not obtainable with such a simple connection, it has been necessary heretofore to employ either a special winding designed with particular reference to the speed ratios required or else to employ a practically prohibitive number of terminal connections. For instance, consider a standard three-phase winding which is to be connected for two different speeds—that is, for two different pole-numbers bearing any desired ratio to each other. Obviously a coil that is connected in the first phase for one speed may be connected in either the first, second, or third phase

45 for the other speed, and some of the coils which are connected similarly with respect to the phase in which they are placed for the two speeds may have their terminal connections relatively reversed, so as to be trav-

ersed by currents in relatively opposite directions—that is, considering the coils which compose any one phase for one of the speeds it would be necessary to split those coils first into three groups, according as they are to be connected in the first, second, or third phase for the other speed, and then to split each of those three groups into two, so as to render it possible to reverse the current in a portion of the coils of each group relatively to the other coils—that is, the coils of each phase must be divided into six groups, making eighteen groups in all. Each group requires two terminal connections. Consequently thirty-six terminal connections are required for connecting the motor for two different speeds. Obviously such a number of terminal connections may be prohibitive in practice.

My invention in one of its aspects consists in connecting the windings of a motor supplied with three-phase current which is to operate at a plurality of speeds in **T** connection for both speeds instead of the ordinary three-phase connection, either delta or **Y**, and in connecting together in a group the coils which undergo similar changes in circuit connections in shifting from one speed to the other. By employing the **T** connection the number of phases inside the motor is reduced from three to two, so that in splitting up the coils into their proper groups the number of necessary groups is reduced. Thus, for instance, if the coils connected in one phase for either speed be considered it is obvious that each coil must be either in that phase or in the other phase for the second speed, and consequently it is necessary to divide the coils of each phase into four groups only, making a total of eight groups and sixteen terminal connections. By properly arranging the groups in the **T** connection certain of them may be permanently connected together, reducing the number of external leads required to thirteen. Obviously a control which would be impracticable with thirty-six leads may easily be commercially possible when only sixteen or thirteen leads are required.

50 A peculiarity of the **T** connection as compared with other polyphase connections is the inequality in the number of coils in the two phases. It is well known in the art that when a **T** connection is employed for three-

phase operation in order to secure a proper balance of the phases the number of coils in one phase should bear to the number of coils in the other phase a ratio approximately equal to the ratio of six to seven—or, more accurately, .86. In other words, the number of coils per pole for a **T** connection should be such that it may be divided into two parts bearing to each other the ratio of approximately six to seven. In other words, the number of coils per pole must be divisible by a number not less than thirteen. Obviously if a large number of poles is required the total number of coils which in ordinary windings must be a multiple not only of the number of coils per pole, but also of the number of poles, may be very large, and when the motor is to operate at a plurality of speeds requiring pole-numbers which contain large factors that are prime to each other the number of coils required may clearly become so large as to be out of the question. For instance, with windings as ordinarily arranged in order to obtain a balanced **T** connection with both an eight-pole and a ten-pole winding a total number of coils would have to be employed divisible by eight, by ten, and by thirteen. Such a number of coils in a small motor would be out of the question.

One feature of my invention consists in a novel method of arranging the connections of a motor in which the number of coils is not a common multiple of the number of poles and the desired number of coils per pole by which the proper relative number of coils in the several phases may nevertheless be obtained. By means of my invention it is possible to use a comparatively small number of coils without sacrificing the proper balance between the phases. My invention in this aspect while of particular value in forming a **T** connection, owing to the large number of coils which would otherwise often be required in connecting the winding in the ordinary manner, is nevertheless not limited to a **T** connection or to a three-phase motor nor even to a multispeed motor, but may be employed wherever it is desired to connect a winding for a given number of poles and phases when the number of coils divided by the number of poles gives a number which is not divisible in the proper proportion between the phases. My invention in this aspect consists in dividing the total number of coils between the phases in proper proportion, then dividing the number of coils for each phase by the number of poles, from which latter division there will be a number of coils left over, and distributing these remaining coils as uniformly as possible among a portion of the poles. A winding arranged in this manner will have an excess or deficiency of a coil at some of the poles; but this excess or deficiency does not injure the efficiency of the motor to any extent and

renders it possible to obtain a complete balance between the phases with respect to the total number of coils per phase.

My invention further comprises an alternating-current motor with a distributed winding having a number of coils in a phase, which divided by the number of poles gives a fractional number, the poles of the phase being formed some of a greater and some of a less number of coils than said fractional number.

My invention further comprises the combination, with an alternating-current motor having its primary winding connected in a plurality of coil groups, of means for establishing a plurality of **T** connections of said winding with the groups arranged in varying relations to each other, the groups being arranged to produce different pole-numbers when their relative connections to each other are varied.

My invention will best be understood by reference to the accompanying drawings, in which—

Figure 1 shows diagrammatically the circuit connections of a motor arranged to operate with three-phase current at a plurality of speeds in accordance with my invention. Figs. 2 and 3 show the connections of the motor-winding established by the controlling-switch of Fig. 1. Fig. 4 is an explanatory diagram showing the method by which the coils are selected for the several groups, and Fig. 5 shows a development on a plane surface of a portion of the motor-winding arranged in accordance with my invention.

In Fig. 1, **S** represents the stator-winding of an induction-motor, which is adapted for connection through the controlling-switch **C** to a source of three-phase current, (indicated by the line-wires **L**.) **R** represents the rotor, which is indicated diagrammatically by a portion of a squirrel-cage winding of the well-known construction. The stator **S** is divided into eight groups, as shown, the relative connections of which to each other are altered when the controlling-switch **C** is shifted from one position to the other.

The connections established by the controlling-switch in its two positions are as shown in Figs. 2 and 3. It will be seen that in both cases the groups are arranged in a **T** connection, but that the positions of the groups in the two arrangements are different. Each group is provided with two reference-letters—one a capital and one a small letter—and with a positive or negative sign. Thus, for instance, one group is provided with the reference character **Aa+**. In Fig. 2 all the groups having the reference-letter **a** are connected in one phase, while the groups having the reference-letter **b** are connected in the other phase. In Fig. 3 all the groups having the reference-letter **A** are connected in one phase, while the groups having the reference-letter **B** are con-

nected in the other phase. Furthermore, the groups having a positive sign have the same relative terminal connections with respect to the direction of current-flow in both arrangements, while the groups having the negative sign have their terminal connections relatively reversed in the two arrangements. The purpose of this notation is as follows: Consider the several groups in Fig. 3 in the phase indicated by A. Reference-letter A signifies that all these groups are connected in this phase for this speed. As has been pointed out before, it is obvious that some of these groups will be connected in the same phase for the other speed, while others of the groups will be connected in the other phase. The groups which are to remain in the same phase are provided with reference-letter a, while the groups which are to be connected in the other phase for the other speed are provided with the reference-letter b. Also, as has been heretofore pointed out, the relative direction of current-flow in some of the groups will be reversed in changing from one speed to another. Consequently the positive and negative signs are employed to indicate the relative reversal of connection. The plus-signs mean that the groups to which they are applied are to have the same relative connections for both speeds with respect to direction of current-flow, while the minus-signs mean that the relative direction of current-flow is to be reversed to those groups in changing from one speed to another. Thus, for instance, both groups $Aa+$ and $Aa-$ will be in the same phase for both speeds; but the terminal connections of the group $Aa-$ will be relatively reversed for the two speeds. This is clearly shown by comparison of Figs. 2 and 3, observing the group terminals which are given corresponding numbers of reference in the two figures. With this preliminary explanation the diagram Fig. 4, illustrating the method of selecting the coils for the different groups, will be readily understood. This diagram shows the method of selecting the groups for T connection for four poles and six poles with a winding having fifty-four coils. The upper row of arrows (indicated by the reference-letter A) indicate the coils which are connected in one phase for the four-pole T connection and the row of arrows B indicate the coils for the other phase for the same number of poles. In order to simplify the diagram as much as possible, a coil is indicated by a single arrow representing by its position the central line of the coil and the direction of the arrow representing the direction of current-flow in the coil. For instance, an arrow pointing upward may be considered as representing the center line of a coil in which the current is flowing in a counter-clockwise direction at any given instant, while an arrow pointing downward indicates the center line of the

coil in which the current at the same instant is flowing in a clockwise direction.

Upon inspecting the arrows in the rows A and B it will be seen that they are arranged in unequal groups. Thus the row A is arranged in four groups in which the arrows number, respectively, 6, 6, 6, and 7, while the arrows in row B are in four groups which number, respectively, 7, 8, 7, and 7. Similarly, the arrows in row a are in six groups, which number, respectively, 4, 4, 4, 5, 4, and 4, while the groups of arrows in row b number 5, 5, 4, 5, 5, and 5, respectively. The reason for this irregularity in the groups will be evident from the following considerations: The diagram represents a winding having fifty-four coils, which must be connected both for four poles and for six poles in T connection. Considering first the six-pole connection, fifty-four coils with six poles gives nine coils per pole, and the number "9" is not divisible in the proper ratio for a T connection. The closest approximation to the proper ratio that can be obtained with nine coils is four to five, or .80, which is too small, since .86 is desired. With the four-pole connection the situation is still worse, since the total number of coils is not evenly divisible by the total number of the poles. Consequently with the symmetrical connections that have been employed heretofore it would be impossible to connect the winding in question as desired in the present case. I accomplish the desired result, however, in the following manner: Instead of attempting to divide the fifty-four coils evenly among the number of poles required I first assign the total number of coils in proper proportion between the two phases. Fifty-four may be divided into twenty-five and twenty-nine, which gives a ratio of .86, which is exactly what is required for the proper phase balance with the T connection. I then take the twenty-five coils which have been assigned to one phase and divide them among the four poles in the first case and among the six poles in the second. In each case one coil remains after an equal division, and this one coil I connect in any one of the poles. When dividing the twenty-nine coils among the four poles, there is similarly an excess of one, which excess coil is connected in a pole of the B phase, which is preferably displaced a maximum amount from the excess-coil pole in the A phase, so that the angular relation of the poles is maintained as uniform as possible. In dividing the twenty-nine coils among the six poles for the second speed there is a deficit of one coil instead of an excess, so I form one coil with only four poles instead of five, and preferably place this pole adjacent to the pole in the a phase having an excess of one coil. In this manner the proper angular positions of the poles are exactly maintained. By the method outlined above

with only fifty-four coils I obtain **T** connections for two different pole-numbers with the phases exactly balanced.

Having thus determined the connections 5 of the coils with respect to the poles of both phases for both speeds and laid out the rows A, B, *a*, and *b*, I next proceed to determine the connections of the coils in their proper groups in the following manner: I first 10 form a row *Aa*+, in which I place a line whenever I find in the rows A and *a* two corresponding arrows having the same direction. Since the presence of these arrows in both the rows A and *a* means that the coils 15 represented thereby are to be connected in the same phase for both speeds and that the relative direction of current remains the same for both speeds all the coils corresponding to the lines in the row *Aa*+, may 20 be connected together in series, care being taken to secure the proper relative direction of current in the coils of the group. This may be taken care of by properly connecting the coils. Thus I have indicated diagrammatically 25 in the line *Aa*+ that the first four coils, beginning at the left, have open-end connections, while the remaining two coils have crossed or closed connections. The reason for this is that the latter coils are indicated in the rows A and *a* by downwardly-pointing arrows, while the others are indicated by upwardly-pointing arrows, showing a current-flow in the opposite direction. I next proceed to form the row *Aa*-, selecting 30 the lines which are common to the rows A and *a*, but in which the arrows point in opposite directions. This opposite direction means that the relative current-flow in these coils will be different for the two speeds. In 35 determining the question of open or closed connections for each coil in this group I have followed the direction of the arrows in row A. Consequently in the four-pole connection the terminal 3 of group *Aa*- will be 40 connected to terminal 2 of group *Aa*+, while for the six-pole connection the terminal 4 will be connected to terminal 2. This corresponds to the connections shown in Figs. 2 and 3, which show the six-pole and the 45 four-pole connections of the groups, respectively. The other groups *Ab*+, *Ab*-, &c., are now selected in the manner that has been already explained, and since all possible 50 combinations are represented by the eight groups all the coils will be included in one group or another. It only remains in establishing the proper connections for the two speeds to have regard to connecting the proper group-terminals to each other. 55 These connections are shown for all the groups in Figs. 2 and 3, and in Fig. 1 a control-switch C is shown with contacts adapted to make the proper connections of the groups, as shown.

65 A portion of the complete winding of the

motor is shown in Fig. 5, in which full coils take the place of the arrows in Fig. 4, and the coils are shown superposed in the way they would be arranged in practice instead of with the coils of the two phases separated, 70 as in Fig. 4. The coils of each group are provided with reference-letters corresponding to the reference-letters of Fig. 4, and the portion of the winding shown in Fig. 5 includes the first thirty-one coils, commencing 75 at the left in Fig. 4. In choosing the coil-pitch it is only necessary to select a width for the coil which will be suitable for both pole-numbers. With fifty-four slots the pole-pitch for the four-pole connection will 80 be thirteen and one-half slots and for the six-pole connection nine slots. This latter number of slots gives a satisfactory coil-pitch for both numbers of poles and has been chosen for illustration in Fig. 5. Any other 85 suitable coil-pitch—such, for instance, as 11 might have been selected instead.

Although for the purpose of giving a complete explanation of my method I have described its application to a motor having two 90 speeds in a specific ratio obtained by specific pole-numbers, it is obvious that my invention is of general application, and in the aspect which relates to employing a **T** connection to minimize the number of leads it is 95 applicable to any motor which it is desired to operate on three-phase current at different speeds, and, further, as regards the method by which I secure a proper balance of the phases with a number of coils not adapted 100 to that end with the ordinary arrangement my invention is not limited to three-phase motors, nor even to multi-speed motors, although for single-speed two or three phase motors the number of coils can ordinarily be so chosen as to render the application of my invention unnecessary. For 105 polyphase motors in general, however, where a number of speeds is required, and particularly in **T**-connected motors, whether arranged for one or two speeds, my invention is 110 particularly useful.

What I claim as new, and desire to secure by Letters Patent of the United States, is—

1. The method of connecting for a given 115 number of poles and phases a winding formed of a number of coils not a common multiple of the number of poles and the desired number of coils per pole, which consists in assigning the proper proportion of the total number of coils to each phase, dividing the number of coils for each phase by the number of poles, and distributing the coils forming the remainder from said division among the poles of that phase, so as to utilize all the 120 coils and to approximate the desired number of coils per pole.

2. The method of connecting for a given 125 number of poles and phases a winding formed of a number of coils not a common multiple 130

of the number of poles and the desired number of coils per pole, which consists in assigning the proper proportion of the total number of coils to each phase, and distributing the coils for each phase as uniformly as possible among the several poles of that phase, so as to utilize all the coils.

3. The method of connecting for a given number of poles and phases a winding having a number of coils for a phase, which, divided by the number of poles, gives a fractional number, which consists in forming the poles of that phase some of a greater and some of a smaller number of coils than said fractional number so as to utilize all the coils to approximate said fractional number at each pole.

4. The method of forming a **T** connection of a given number of poles with a winding which divided by the number of poles gives a number not divisible in the proper ratio for a **T** connection, which consists in dividing the total number of coils into two sets bearing to each other approximately the proper ratio for a **T** connection in respect to number of coils, and each set being distributed as uniformly as possible among the several poles.

5. The method of operating at a plurality of speeds a motor supplied with three-phase currents, which consists in selecting the proper coils for making a **T** connection for each number of poles corresponding to a desired speed, connecting in groups the coils which undergo similar changes in circuit connections in shifting from one number of poles to another, and varying the connections of said groups to obtain the desired speeds.

6. The method of operating at a plurality of speeds a motor supplied with three-phase currents, which consists in selecting the proper coils for making a **T** connection for each number of poles corresponding to a desired speed, and varying the connections of said coils to produce the proper **T** connections for the desired speeds.

7. In a dynamo-electric machine, a distributed winding having a number of coils in

a phase which, divided by the number of poles gives a quotient having a remainder, the coils forming the remainder being distributed among a portion of said poles and all the coils being connected in circuit.

8. In a dynamo-electric machine, a distributed winding having a number of coils in a phase which divided by the number of poles gives a fractional number, the poles of the phase being formed some of a greater and some of a less number of coils than said fractional number.

9. In a dynamo-electric machine, a distributed winding arranged in **T** connection and formed of a number of coils which divided by the number of poles gives a number not divisible in the proper ratio for a **T** connection, the total number of coils being divided into two sets bearing to each other approximately the proper ratio for a **T** connection in respect to number of coils, and each set being distributed as uniformly as possible among the several poles.

10. In combination with an alternating-current motor, means for establishing a plurality of **T** connections of the motor-windings with different pole-numbers, the coils which undergo similar changes in circuit connections in shifting from one number of poles to another being permanently connected in a group.

11. In combination with an alternating-current motor having its primary winding connected in a plurality of coil groups, means for establishing a plurality of **T** connections of said winding with the groups arranged in varying relations to each other, said groups being arranged to produce different pole-numbers when their relative connections to each other are varied.

In witness whereof I have hereunto set my hand this 8th day of November, 1905.

ERNST F. W. ALEXANDERSON.
